UNITED STATES PATENT OFFICE.

EDWARD N. JACOBI, OF MILWAUKEE, WISCONSIN, ASSIGNOR, BY MESNE ASSIGNMENTS, TO BRIGGS & STRATTON CORPORATION, OF MILWAUKEE, WISCONSIN, A CORPORATION OF DELAWARE.

EXTENSION SWITCH.

Application filed July 21, 1917. Serial No. 182,040.

To all whom it may concern:

Be it known that I, EDWARD N. JACOBI, a citizen of the United States, and resident of Milwaukee, in the county of Milwaukee and State of Wisconsin, have invented new and useful Improvements in Extension Switches, of which the following is a description, reference being had to the accompanying drawings, which are a part of this specification.

This invention has for its object to provide an automobile switch with the switch mechanism distant from the handle mechanism and suitably connected therewith by extensible and flexible means to permit of variation in angularity and distance between the handle mechanism and the switch mechanism to accommodate the variation incident to the use of metal instrument boards and cowl dash constructions.

Another object of the invention is to provide such an extension switch construction without loose parts liable to rattle when the automobile is in motion.

Another object of the invention is to provide an extension switch of this character which will constitute a lock switch and which will control the lighting circuits as well as the ignition circuit.

With the above and other objects in view the invention consists in the extension switch as herein claimed and all equivalents.

Referring to the accompanying drawings in which like characters of reference indicate the same parts in the different views:

Fig. 1 is a longitudinal sectional view of an extension switch constructed in accordance with this invention;

Fig. 2 is a front view thereof;

Fig. 3 is a sectional view on the plane of line 3—3 of Fig. 1 showing the cam operated lock mechanism;

Fig. 4 is a perspective view of the lock cam;

Fig. 5 is a sectional detail view on a plane at right angles to the plane of Fig. 1 showing the tubular driver connecting the lock cam with the operating rod;

Fig. 6 is a sectional view on the line 6—6 of Fig. 1 showing the connection between the inner operating parts and the connection between the outer operating parts;

Fig. 7 is an end view of the driver clutch;

Fig. 8 is a face view of the thrust plate; Fig. 9 is a perspective view of the operating dog;

Fig. 10 is a view similar to Fig. 1 of a modified form of the invention;

Fig. 11 is a transverse sectional view thereof on the plane of line 11—11 of Fig. 10;

Fig. 12 is a sectional view of parts on the plane of line 12—12 of Fig. 11, the cam follower and the pusher being separated from the cam for clearness;

Fig. 13 is a sectional view through the switch handle showing the operating cup on the end of the rod;

Fig. 14 is a detail view of the key guide centering cup;

Fig. 15 is a detail view of the cam follower; and,

Fig. 16 is a detail view of the key.

In these drawings 15 indicates a switch case riveted or otherwise secured to a thin sheet metal plate 16 which is slightly dished and is somewhat flexible in order to permit the switch to be inclined one way or another for alignment with its operating means. This plate may be riveted or otherwise secured to the base 17 which may in turn be secured to the dash board 17. A terminal head 18 of insulating material is secured to the switch case and forms therewith a housing in which is located a switch mechanism of a well known type, though any other switch mechanism may be substituted. The insulating contact disk 19 is secured to a flanged driver chuck 20 fitting through an opening in the casing and is turned thereby to move the radial spring contact arms of the spider 21 into engagement with recessed contacts studs 22 embedded in the terminal head to effect the different lighting combinations for controlling the lighting circuits of the automobile.

A locking bolt 23 slides in a space provided for it in the driver chuck and is moved into and out of locking engagement with openings 24 in an inturned flange 100 of the switch case by means of a cam 25 on a short spindle or lock member 26 which has a slotted head contained within a recess of the driver chuck and a stem portion passing through a central opening in the insulating disk 19. The end of the spindle 26 is

flattened to form a flange fitting in a central slot of an insulating connecting member 27 so that when the spindle is turned said connecting member is turned and serves 5 to rotate a pair of concentrically mounted brush arms 28 having bent portions engaging notches thereof. The rotation of the brush arms causes them to engage alternate pairs of contact segments for controlling the 10 ignition circuit of the automobile and incidentally changing the polarity thereof.

The switch handle 29 is rotatably mounted in a front plate 30 secured in any desired manner to the instrument board or cowl 15 dash 31. A thrust plate 32 is mounted on the handle and has a bearing on the front plate to hold the handle in place and an operating tube 33 is fastened to the thrust plate as by riveting lugs on the end thereof 20 through openings in the thrust plate and serves to communicate motion from the rotary handle to the driver clutch 20 in order to rotate the contact disk 19. The slip connection between the driver clutch 20 and 25 the operating tube 33 is formed by the slotted end of the tube so as to leave a pair of parallel fingers 34 diametrically opposite and engaged between a pair of opposite outstanding parallel horns 35 on the driver 30 chuck 20. These interfitting fingers and horns allow of the handle being positioned at various distances from the switch mechanism without losing their driving connection communicating the turning movements 35 of the handle to the contact disk.

In order to communicate the movements of the key in the handle to the spindle 26 for operating the lock bolt 23 and for turning the ignition switch, an operating rod 36 is 40 provided within the operating tube and adapted to be turned by the key and serving to turn a driver sleeve 37 which fits within the driver chuck 20 and is engaged with the spindle. The flat key 38 is adapted 45 to be entered through a slot 39 in the end of the handle 29 and is guided by a key guide 40 into a groove 41 in the end of an operating dog 42 which is rotatably mounted in the handle 29. This operating dog 50 42 has a shoulder bearing against a corresponding shoulder in the bore of the handle to form an end thrust bearing and is confined in place by the thrust plate 32, while the end of the operating rod 36 has 55 its end locked within an opening thereof by a pin 43 passing through the dog and the end of the rod. The other end of the operating rod telescopes within the driver sleeve 37 and is slotted to receive a pin 44 60 which extends across the opening of the sleeve. The driver sleeve is confined within the driver chuck member 20 by engaging with inwardly projecting flanges 45 at the ends of the horns 35, while the other end of 65 the sleeve is formed with a pair of oppo-

site driving lugs 46 engaging a slot across the end of the enlarged head of spindle 26. The variation in spacing of the switch handle from the switch construction will be accommodated by the play of the pin 44 in 70 the slot of the operating rod 36 and the turning movements of the key will be transmitted through the operating rod 36 and the driver sleeve 37 to the spindle 26 to control the lock bolt and to operate the ignition 75 switch. Spring pawls 47 on the driver chuck member 20, as seen in Fig. 3, may engage ratchet teeth 48 on the head of spindle 26 to permit said spindle to turn in one direction only, thus compelling the proper 80 operation for reversing the polarity of the ignition circuit.

In order to prevent the rattle of loose parts a coil spring 49 is housed within the operating tube 33 and bears at one end 85 against the inwardly projecting flanges 45 of the horns of the driver chuck and against a spherical collar 50 secured on the operating rod 36. The spring serves to hold the operating rod in its end thrust bearing and 90 at the same time press the driver chuck against its end thrust bearing. The collar 50 fits within the operating tube 33 so as to keep the rod 36 centrally positioned 95 therein.

For installing the switch of this invention it is not necessary to carry the wiring through the space between the cowl dash and the dash board where it is difficult to properly handle it, but the wiring may be 100 carried on the front of the dash board where the switch mechanism is located. It is almost impossible to obtain accurate registration of an opening in the cowl dash for switch 105 handle mechanism and an opening in the dash board for the switch operating connection. These openings are consequently made large to leave a clearance around the operating connection that will enable the parts to be positioned as desired. The switch handle 110 mechanism may be secured in place on the cowl dash or instrument board and then the switch mechanism may be coupled therewith and secured to the dash board. The 115 slideable coupling for the operating members makes it unnecessary to cut parts in order that they may fit, for they merely telescope more or less to accommodate the variation in the distance between the dash board and cowl dash that will unavoidably occur in 120 different cars of the same make. Furthermore, the flexibility of the thin sheet metal plate 16 permits the switch mechanism to be properly aligned with the handle mechanism enabling the parts to fit together without binding when the edge of the front plate 30 and the dash board 17 are not in parallel planes. Thus the thin sheet metal plate 16, because of its flexibility and because of its being slightly dished, constitutes 125 130

a yielding flexible support for the switch for automatically obtaining adjustment of the position of the switch to bring it into axial alignment with the handle.

6 The switch structure of this invention is quickly and easily installed without cutting and fitting of parts and without requiring extreme accuracy in the workmanship.

10 By inserting the key 38 in the key opening 39 it engages the groove 41 of the operating dog so that when it is turned it turns the operating rod 36, the driver sleeve 37, the spindle 26 and the insulating connector disk 27, thus turning the contact

15 brushes 28 to render the ignition circuit effective, while at the same time through the turning of cam 25 withdrawing the locking bolt 23 to a position for unlocking the lighting switch.

20 While the switch is unlocked the handle 29 may be turned to any desired position for controlling the lighting circuits, the movement of the handle being imparted through the operating tube 33 and

25 the driver chuck 20 to the contact disk 19. The key is preferably seated in notches in the handle member 29 so as to turn therewith, the contact segments of the pole reversing ignition switch being of sufficient

30 length to permit the arc of movement without losing contact with the brushes 28.

35 It is to be understood that the invention is not limited to any specific form or arrangement of parts except in so far as such limitations are specified in the claims.

The particular details of construction of the switch are not essential to the invention and various other parts may be changed without departing from the invention. In

40 the construction shown in Figs. 10 to 15, inclusive, and forming a modification of the invention, the lighting switch is not locked by the removal of the key for the ignition switch but is independent thereof so that

45 the lights may be controlled as desired when the car is locked as well as when the ignition circuit is operative. Other changes in details of construction are made in this modification.

50 In this modification the switch case 15' is of substantially the same construction as in the other form of the invention, but the terminal head 18' thereof carries a simple ignition switch contact spring 28', adapted to

55 be forced against the contact stud 28" for closing the ignition circuit of a battery ignition system. The movement of the switch contact spring 28' is effected through a pusher 26', preferably of insulating material and passing through a central opening

60 in the contact disk 19'. The end of the pusher 26' is reduced in diameter and passes through a central opening in a cam 60 which has helical cam arms guided in grooves of

65 the chuck 20'. The driver sleeve 37' has an

enlarged head 61 with a central recess 62 within which slidably fits the reduced end of the pusher 26', and also has a pair of cam surfaces 63 fitting against the cam surfaces of the cam member 60 so that when the 70 driver is turned in one direction the co-operation of these cam surfaces forces the cam member to slide in the chuck and force the pusher 26' against the pressure of the ignition switch contact spring 28', moving 75 it into engagement with the contact stud 28". When the driver is turned in the other direction, these cam surfaces permit the ignition switch contact spring 28' to move out of engagement with the contact stud and 80 return the parts to their original position. The head of the driver 37' bears against a shoulder on the chuck 20' and has an offset projection 64 to bear against the surface of the contact disk 19'. It is thus held in place 85 by the two bearing means against longitudinal displacement. Instead of a pin across the driver sleeve for engaging the slotted end of the operating rod 36', key ribs 65 project inwardly at opposite sides thereof and engage the slot of the operating rod, 90 as seen in Fig. 11.

The coil spring 49' is of larger diameter at its middle portion so as to bear outwardly against the operating tube 33', while its 95 ends tightly engage the operating rod 36', thus serving to center the operating rod. At one end the spring bears against the inwardly projecting flanges 45' on the horns of the driver chuck as before, while at its 100 other end it bears against a collar 66 of the clinch washer type engaged in a groove around the operating rod. The horns of the driver chuck in this form of the device are formed by projections inside of the bore of the chuck which is tubular, forming a housing to enclose the overlapping parts of the operating connections.

The thrust plate 32', instead of being riveted on the end of the operating tube 33', has lugs 67 entered through openings near the end of the operating tube, such end of the operating tube fitting within the bore of the lighting switch handle 29'. The operating dog 42' for the end of the operating 115 rod, is in the form of a cup contained within this bore of the switch handle and bearing on the end of the operating tube and having the operating rod riveted thereto. The end of the operating rod is shouldered by having parallel flat faces formed thereon, and the opening through the operating dog 42' has parallel edges to fit thereon and engaged by the opposite edges of the rod for riveting it in place. The opening in the 120 operating dog forms a continuation of the key groove 41' in the end of the rod to be engaged by the spaced lugs at the end of the key 38'. Between the operating dog 42' and the shoulder in the bore of the switch han-

125

130

dle, is a dished centering cup 68 with a central opening fitting around the end of the key guide 40', and allowing the end of the key to pass therethrough. The centering cup turns with the key guide and holds it in proper position to guide the key to the groove in the end of the operating rod.

In order that there should be a guide stop to determine the position of the key in 10 which it registers with the key opening of the handle, a lug 69 is bent outwardly from the operating dog 42' and travels in a recess in the bore of the switch handle and engages the end of said recess for that purpose.

15 It will be noted that with this construction there is the same facility for centering the operating means with the switch mechanism and that the parts are free from binding, a sufficient play being permitted between the coupling members to give them what is in effect a universal joint without 20 permitting rattling. The shape and position of the spring 49' assist in preventing the rattling of parts, serving to centrally space 25 the rod 36' within the tube 33' and pressing the rod and the operating parts attached thereto into end thrust bearing, while also pressing the driver chuck and the parts attached thereto into end thrust bearing. The 30 pressure of the ignition contact spring serves to hold the driver 37' in its end thrust bearing.

The frictional engagement between the two switch operating means causes the operating rod and its parts to turn when the switch handle is turned for controlling the lighting circuit, thus their relative position remains the same and the cam for operating the pusher remains ineffective for changing 35 the position of the ignition switch. In any position of the lighting switch, however, the key may be turned to cause the cam to move the pusher and so operate the ignition switch to either lock or unlock the car. The 40 stop lug 69 by striking the shoulder at the end of the recess in which it travels, positions the key in register with the key hole slot in the handle member.

It will be noted that in both forms of the 50 invention the extensible driving connections between the switches and their operating means have their engaging faces in parallel planes with comparatively close fit, while having comparatively loose fit with other 55 parts, thus permitting them to have pivotal movement with each other to compensate for slight angularity between the handle mechanism and the switch mechanism. In compensating for this angularity these joints act 60 as universal joints.

What I claim as new and desire to secure by Letters Patent is:

1. An automobile switch, an irregularly 65 positioned handle distant therefrom, a shaft connection between the switch and handle,

and means permitting adjustment of the position of the switch for axial alignment with the handle.

2. A switch having a variably distant handle, extensible shaft connecting means 70 between them, and means permitting adjustment of the switch for axial alignment with the handle.

3. A switch having a distant handle, a shaft connection between them, and compensating means for maintaining axial alignment between the switch and its handle. 75

4. A switch having a distant handle, shaft connecting means between them, and a flexible support for the switch permitting its 80 axial alignment with the handle.

5. An automobile switch, a handle distant therefrom, a shaft connecting the same, bearing plates for each end of the shaft adapted to be secured to the dash-board and 85 the instrument board, and means for permitting a universal angular adjustment of the shaft with relation to one of the attaching plates to compensate for non-parallelism 90 of the supporting elements. 90

6. In an automobile switch, a double switch structure, a double handle mechanism variably distant therefrom, and concentric extensible driving connections between the switch structure and the handle 95 mechanism.

7. An automobile lock switch comprising a switch structure, a lock member, a distant handle, operating means connecting the switch structure with the handle, and key 100 operated means on the handle having connection with the lock member.

8. An automobile lock switch comprising a switch mechanism, a lock member therefor, a distant handle, key operated means 105 on the handle, and concentric means for connecting the handle and the key operated means with the switch mechanism and the lock member respectively.

9. An automobile lock switch, comprising 110 a switch mechanism, a lock member therefor, a variably distant handle, a key operated means on the handle, and extensible operating means connecting the handle and the key operating means with the switch 115 mechanism and the lock member respectively.

10. An automobile switch, comprising a switch mechanism, a lock member therefor, a variably distant handle, a key operated means on the handle, and concentric extensible operating means connecting the handle and the key operated means with the switch mechanism and the lock member 120 respectively. 125

11. An automobile switch, comprising a suitably mounted handle member, a key operated means therein, an operating tube connected with the handle member and terminating in parallel fingers, an operating rod 130

- within the operating tube connected with the key operated means and having a slot in its end, a switch mechanism having a switch member, a driver chuck connected with the switch member and provided with a pair of projecting horns interfitting with the fingers of the operating tube, a lock member for the switch member, a driver sleeve fitting within the driver chuck and having connection with the lock member, and a pin across the driver sleeve engaging the slot of the operating rod.
12. An automobile switch, comprising a suitably mounted handle member, a key operated means therein, an operating tube connected with the handle member and terminating in parallel fingers, an operating rod within the operating tube connected with the key operated means and having a slot in its end, a switch mechanism having a switch member, a driver chuck connected with the switch member and provided with a pair of projecting horns interfitting with the fingers of the operating tube, a lock member for the switch member, a driver sleeve fitting within the driver chuck and having connection with the lock member, a projection on the horns of the driver chuck engaging the driver sleeve, a pin across the driver sleeve engaging the slot of the operating rod, a collar on the operating rod, and a coil spring surrounding the operating rod and bearing at one end against the collar and at the other end against the driver chuck.
13. An automobile switch, comprising switch mechanisms, a variably distant handle, a key operated means on the handle, and extensible operating means connecting the handle with one switch mechanism and the key operated means with the other switch mechanism.
14. An automobile switch, comprising a lighting switch and an ignition switch, a distant handle for the lighting switch, and key controlled means accessible through an opening in the handle for operating the ignition switch, the handle for the lighting switch being independent of the key controlled means.
15. An automobile switch, comprising a lighting switch and an ignition switch, a variably distant handle for the lighting switch, a key controlled means for operating the ignition switch contained within the handle but independent thereof, and concentric connecting means between the handle and the lighting switch and between the key controlled means and the ignition switch.
16. An automobile switch, comprising a lighting switch and an ignition switch, a handle for operating the lighting switch, a key controlled means within the handle having engagement therewith to maintain it in a fixed relation thereto, and means dependent upon a relative movement between said handle and said key controlled means for operating the ignition switch.
17. An automobile switch, comprising a lighting switch and an ignition switch, a handle for operating the lighting switch, a key controlled means accessible through an opening in the handle and having engagement with the handle for maintaining it in a fixed relation thereto, and a cam means operated by a relative movement between the key controlled means and the handle for operating the ignition switch.
18. An automobile switch, comprising a lighting switch and an ignition switch, a distant handle having an extensible operative connection with the lighting switch, a key controlled means within the handle engaging the handle to maintain a fixed relation therewith, a cam member having an extensible driving connection with the key controlled means, and a cam operated by the cam member for moving the ignition switch.
19. An automobile switch, comprising a switch casing, a rotary contact member mounted therein, a chuck member secured to the rotary contact member and provided with a tubular extension containing longitudinal ribs, a pusher passing through an opening in the contact member, an ignition switch operated thereby, a cam engaging the pusher, a cam driver member seated within the chuck and having a cam face to engage the cam and having a tubular extension provided with longitudinal ribs, a variably distant handle member, an operating tube projecting therefrom, and a key controlled operating rod within the operating tube, said operating tube and said operating rod having their ends slotted to receive the longitudinal ribs of the chuck and the driver member respectively.
20. An automobile switch, comprising a switch casing, a rotary chuck member therein, a clutch secured to the switch member and having a tubular extension with longitudinal ribs, a pusher passing through an opening in the contact member, a switch operated by the pusher, a cam mounted on the pusher and guided by the chuck, a cam-faced driver member seated within the chuck and engaged by said cam and provided with a tubular extension having longitudinal ribs, a distant handle member, an operating tube connected therewith, a key controlled operating rod within the operating tube, said operating tube and said operating rod having their ends slotted to receive the longitudinal ribs of the chuck and the driver member respectively, projections on the end of the chuck member passing through the slots of the operating tube, a coil spring within the operating tube bear-

ing at one end against such projections, and a collar fixed on the operating rod and having the other end of the coil spring bear thereon, said coil spring being of larger diameter at an intermediate point to permit it to bear against the walls of the operating tube at such point while engaging the operating rod at its ends.

21. An automobile switch, comprising a 10 lighting switch and an ignition switch, a distant handle for the lighting switch, an operating tube with its end fitting in an opening in the handle, a thrust plate fixed on the operating tube and secured to the 15 handle, a cup-shaped dog within said opening of the handle, an operating rod secured to said dog and having a key receiving slot at its end, a lug projecting from the dog and having limited movement within the 20 handle, and a key adapted to enter the opening of the handle and engage the operating rod, said operating tube and said operating rod having connection with the lighting switch and the ignition switch respectively.
22. An automobile switch, comprising a 25 lighting switch and an ignition switch, a distant handle, an operating tube fitting in

an opening in the handle and secured thereto, an operating rod within the tube, a dog fitting within said opening and having an 30 opening through which the end of the operating rod is riveted, there being a slot in the end of the operating rod and an opening in the dog to receive a key, a centering cup held within the opening of the handle between a shoulder thereof and the said dog, said centering cup having an opening 40 through which the key may pass and also having a larger central opening, and a U-shaped key guide contained within the opening of the handle and positioned within the central opening of the centering cup to guide the key to the slot in the end of the operating rod, said operating tube and said operating rod having connection with the 45 lighting switch and the ignition switch respectively.

In testimony whereof, I affix my signature, in presence of two witnesses.

EDWARD N. JACOBI.
